UNITED STATES PATENT OFFICE.

GEORGE WESTINGHOUSE, OF PITTSBURG, PENNSYLVANIA.

ELASTIC-FLUID TURBINE.

No. 807,146.

Specification of Letters Patent.

Patented Dec. 12, 1905.

Application filed May 2, 1905. Serial No. 258,484.

To all whom it may concern:

Be it known that I, GEORGE WESTINGHOUSE, a citizen of the United States, and a resident of Pittsburg, in the county of Allegheny and State of Pennsylvania, have invented a new and useful Improvement in Elastic-Fluid Turbines, of which the following is a specification.

This invention relates to elastic-fluid turbines.

It has been found in practice that the rotors and stators of elastic-fluid turbines are liable to and do distort under certain conditions. It is essential to the efficiency of such machines to have the clearances between the relatively moving parts small, and to overcome the troubles which arise from small clearances and said distortions has been an object of this invention.

In the drawings accompanying this application, and throughout the several views of which similar elements are denoted by like characters, Figure 1 is a view, partially in section and partially in elevation, of a fragmentary portion of a turbine equipped with this invention. In this view the blades or vanes, as the case may be, are shown unshrouded, but lashed together by any suitable means. Fig. 2 is a view similar to Fig. 1, but in this view the blades or vanes are shown shrouded. Fig. 3 is a view in perspective of a fragmentary portion of a turbine equipped with this invention. Fig. 4 is a view in sectional elevation of a portion of a turbine-stator equipped with a modification of this invention shown in line with the rotor-blades.

In carrying this invention into effect the holding element for either the blades or the vanes, which may be either the rotor or the stator, is provided with circumferential undercut slots or channels 4 in line with the rows of blades or vanes carried by the other holding element, which may be the rotor or stator. Into these slots or channels 4 a segmental ring 5 is threaded. This ring is provided with a flange portion 6, which lies within the undercut portion of the channel below the overhung portion 7, which overhung portion serves as an abutment for limiting the outward radial movement of the ring. A spring 8, of any suitable form, lies within the channel beneath the ring 5 and tends to yieldingly hold said ring in its outward position, or so that its flange 6 lies in contact with the overhung portion 7 of the channel.

As the turbine casings or stators are commonly divided on the horizontal plane through the turbine-axis, these ring-segments 5 are easily inserted within the channels of the stator. If they are employed on the rotor, however, it will be necessary to have a section of the overhung portion 7 removable, as at 10 in Fig. 1, and the length of this removable portion will have to be slightly longer than the segments of the ring 5. This removable portion 10 may be secured in place by screws or any other suitable means. It will be understood that by employing this device in a turbine the clearances beyond the ends of the blades or vanes may be reduced to a minimum, and the top edge of the ring 5 may lie just out of contact with the ends of the blades or vanes or the shroud with which they may be provided. If distortion does occur and the blades or vanes contact with the ring, the same will yield and move outwardly to accommodate such distortion.

In the modified form shown in Fig. 4 each of the clearance-determining rings is provided with a flange portion 11, which extends longitudinally of the turbine-axis and below the outer ends of the rotor-blades. The stator or casing is cut away, as shown at 12, to accommodate this flange portion when the same is moved toward the stator under pressure due to the blades contacting therewith. This form will only be used when the blades are unshrouded.

This invention is applicable to turbines of various types and is not limited to the type illustrated, and it will be understood that various other modifications may be made in this device without departing from the spirit of this invention.

Having thus described this invention, what I claim is—

1. In an elastic-fluid turbine, in combination with the annular rows of rotor-blades, clearance - determining rings yieldingly mounted in the stator in line with said rows.
2. In an elastic-fluid turbine, in combination with the annular rows of rotor-blades, radial clearance-determining rings yieldingly mounted in the stator in line with said rows.
3. In an elastic-fluid turbine, in combination with the annular rows of rotor-blades, clearance - determining rings yieldingly mounted in the stator adjacent to the outer ends of the blades in said rows.
4. In an elastic-fluid turbine, in combina-

tion with the annular rows of rotor-blades, a stator, channels in said stator in line with said rows, segmental clearance-determining rings located in said channels and means 5 tending to yieldingly hold said rings toward the blades of said rows.

5. In an elastic-fluid turbine, in combination with the annular rows of blades or vanes thereof, clearance-determining rings loosely 10 mounted adjacent to the free ends of said blades or vanes, means limiting the movement of said rings toward said blades or vanes and resilient means tending to yieldingly hold said rings toward the limit of said 15 movement.

6. In an elastic-fluid turbine, in combination with the annular rows of rotor-blades, clearance - determining rings yieldingly mounted in the stator in line with said blades 20 and each of which is provided with a flange portion extending longitudinally of the tur- 30

bine-axis and normally beyond the stator- surface.

7. In an elastic-fluid turbine, in combination with annular rows of shrouded rotor-blades, clearance - determining rings yieldingly mounted in the stator adjacent to the blade-shrouds. 25

8. In an elastic-fluid turbine, in combination with an annular row of rotor-blades, a shroud covering the outer ends of a plurality 30 of said blades, a segmental clearance-determining ring loosely mounted in the stator adjacent to said shroud, and a spring tending to yieldingly force said ring toward said shroud. 35

In testimony whereof I have hereunto subscribed my name this 24th day of April, 1905.

GEO. WESTINGHOUSE.
